UNITED STATES PATENT OFFICE.

CHARLES FASOLDT, OF GRAND RAPIDS, MICHIGAN.

GARMENT-BUCKLE.

1,208,531.

Specification of Letters Patent. Patented Dec. 12, 1916.

Application filed November 15, 1915. Serial No. 61,700.

To all whom it may concern:

Be it known that I, CHARLES FASOLDT, a citizen of the United States, residing at Grand Rapids, in the county of Kent and State of Michigan, have invented certain new and useful Improvements in Garment-Buckles, of which the following is a specification.

My invention relates to improvements in buckles for use for supporting wearing apparel, as pantaloons, overalls and kindred articles, and its object is to provide a buckle having a thoroughly reliable, readily adjustable spring button loop with which buttons having various sizes of necks may be readily entered and secured in the loop. I attain this object by the construction and arrangement of parts shown in the accompanying drawing, in which—

Figure 1 is an elevation, and Fig. 2 is an edge view of one form of buckle, and Figs. 3 and 4 are like views of another form of buckle embodying my invention.

Similar letters refer to similar parts throughout the several views.

In the accompanying drawing, speaking, now, more particularly of Figs. 1 and 2, *a* represents the buckle loop, *b*—*b* represent the tongues of the buckle, and *c*—*c* represent the side bars of the frame of the buckle. In the construction of this form of buckle the loop *a* is made in a piece by itself, and the tongues *b* and the side bars *c* of the frame are made integral and the lower ends 35 of the side bars *c*, *c* are so twisted, or wound around the two members of the loop *d* as to render the connection absolutely firm and to avert the possible danger of the loop *d* sliding longitudinally in said bearings. The 40 arms *d'*, *d''* of the loop *d* are bent upward at *d''* and made practically of the form indicated at *e*, *e* to form the loop *k*. The lower end of the loop *k* should be practically closed, or the wires at the bends *d''* should 45 be close enough together to avert any possible danger of the neck of a button passing through between them, but the opening at *k'* should be considerably broader, as indicated in Figs. 1 and 3, so a button neck may 50 be passed between the ends of the wires *e*, *e* without the necessity of forcing them apart to too great an extent. This wire must be spring wire so it will assume its normal position when the button has been inserted or 55 removed.

In Figs. 1 and 2 the ends of the wires *e*, *e* are represented as standing unsupported except by the main wire or arm *d'*, but in Figs. 3 and 4 I have shown each side of the body of the buckle, (C, C) as having a bearing 60 *c'* formed in it, and the ends of the wires *e*, *e* as extended outward, practically at right angles with the loop wires *e*, *e* and passed through the bearings *c'*, as indicated at *e'*, *e'*, so there can be no possible danger of the 65 wires *e*, *e* being bent over sidewise by excessive strain on a button.

Sufficient space should be left between the arms *d* and *d'* of the loop 1 to freely receive the strap or other element on a garment that 70 is to be connected with the buckle.

The form of connection between the side bars *c*, *c* of the buckle, and the ends of the wire *d*, *d'* (as shown at *f* and *g*) is not given as a restricted form, but as one of 75 many forms of connection between these two elements.

In Fig. 2, I have represented, at *i*, a strap, and at *j* a button secured thereto and placed in engagement with the loop *k*, formed by 80 the ends *e*, *e*, to indicate how the two are connected, and applied to the loop.

In the several figures herewith I have shown but two, of many available, and perhaps equally desirable forms of construction, as indicating that I do not desire to restrict myself to any particular form or construction, but do desire to cover any construction that may be legitimately claimed by me under the state of the art 90 as it may be found to exist.

What I claim as new, and desire to secure by Letters Patent of the United States, is:—

1. In a garment buckle, a buckle loop, 95 side bars pivotally connected with the buckle loop and having buckle tongues integral therewith, a strap loop securely connected at each end with the side bars, and the free ends of the wire from which the 100 strap loop is made extending toward the buckle loop and formed to produce an open button loop at the strap loop attaching end of the buckle frame.

2. In combination with a garment buckle, 105 side bars pivotally connected with the buckle loop at one end, and rigidly connected with a strap loop at the other end, the ends of the strap loop bent inward in serpentine form to form a button loop, and 110

thence bent at right angles, extending outward, and adjustably supported by the side bars of the buckle.

3. In combination with a garment buckle, 5 side bars pivotally connected with the buckle loop, and firmly connected with a strap loop at the lower ends, each side of the buckle frame arranged to form a hole through it laterally, wires extending relatively inward from the strap loop in serpentine form to form a button receiving loop, the ends of said wires bent at right angles and extending through the holes in the side bars of the buckle frame.
- 15 4. In a garment buckle, a frame having a buckle loop at one end and a strap loop at

the other end, in combination with serpentine wires extending from the longitudinal center of the strap loop toward the buckle loop to form the spring sides of a 20 button loop.

5. In combination with the side bars and loop of a buckle frame, the side bars having holes through them laterally, wires extending inward from the lower end of the 25 frame in position to form the spring sides of a button loop, the ends of said wires bent outward and passed through the holes in the side bars of the frame.

Signed at Grand Rapids, Michigan, No- 30
vember 12, 1915.

CHARLES FASOLDT.
